UNITED STATES PATENT OFFICE

PAUL NAEHER, OF CHICAGO, ILLINOIS, ASSIGNOR TO B. T. GUMP CO., OF CHICAGO,
ILLINOIS, A CORPORATION OF ILLINOIS

BAG SEALING MECHANISM

Application filed September 8, 1931. Serial No. 561,623.

This invention relates to tape applying mechanism for a bag sealing machine and primarily concerns itself with means for shaping and retaining the sides of the bag 5 while the tape is being applied over the top and down the ends of the bag.

It has been found in practice that if the sides of the bag are not properly supported or retained from bulging outwardly when 10 the tape is being rolled over the top and over the ends of the bag, there is more or less kinking or distortion at the corners of the bag. It is an object of this invention to overcome this objection in the provision of side 15 plates that move down in advance of the tape applying rollers for holding the sides of the bag against bulging while the rollers apply the tape.

The invention comprises the novel structure and combination of parts hereinafter described and more particularly set out and defined in the appended claims.

In the accompanying drawings which illustrate a preferred form of this invention 25 and in which similar reference numerals refer to similar features in the different views:

Figure 1 is a sectional view through a bag closing machine illustrating the tape applying mechanism in elevation.

Figure 2 is an enlarged sectional view taken upon the line II—II of Figure 1 looking in the direction of the arrows and showing parts in elevation.

Figure 3 is a fragmentary and elevational view of the machine upon an enlarged scale.

Figure 4 is a fragmentary sectional view taken upon the line IV—IV of Figure 1 looking in the direction of the arrow and showing parts in elevation.

In order to illustrate this invention, parts of the bag closing and sealing machine have been illustrated. The bag to be folded and sealed is adapted to be conveyed along a longitudinally extending platform 1 having side rails 2. The platform is positioned a short distance below the table or bench 3 which supports the operating mechanism. A pair of vertical rods or standards 4 are supported upon the bench 3. A block 5 is mounted upon the standards 4 for reciprocating

movement. This block 5 carries a lateral bar or support 6 upon which a pair of side plates 7 are adjustably mounted. These side plates have upper angle clips 8 which are attached to the support 6 by means of bolts 9 which pass through slots 10 in the bar 6 whereby said plates may be laterally adjusted for different sizes of bags. Between the plates 7 there is a top plate 11 which is adapted for pressing against the top of the bag. Above 60 the block 5 which in reality constitutes a cross-head, there is a second cross-head 12 which is slidably mounted upon the standards 4. The cross-head 12 is normally urged upwardly against an adjustable stop 13 by means of coil springs 14. A pair of spaced shafts 15 are carried by the cross-head 12 for rotatable movement and each of the shafts 15 carries an arm 16 which has a tape applying roller 17 journaled thereon. These arms 70 are normally pressed against the ends of the bag by means of a coil spring 18 which connects the two arms as shown in Figure 4.

The different cross-heads are adapted to be reciprocated downwardly by the following mechanism:

A shaft 19 which is suitably journaled in the machine constitutes the driving shaft and this shaft is equipped with a segmental gear 20 having a cam 21 attached to its rear face. 80 The segmental gear 20 is adapted for engaging a rack 22 attached to the cross-head 12 and the cam 21 is adapted to engage a stud or roller 23 attached to the cross-head 5. Consequently, when the gear 20 is rotated the two cross-heads will be simultaneously lowered so that the plates 7 will engage the sides of the bag and shape the same and retain it from bulging outwardly while the rollers 17 press the tape against the ends of the bag. 85 As the cross-head 6 descends, the compression plate 11 will apply the tape upon the top of the bag.

In the drawings, there is shown a bag B having a piece of tape T applied over the top thereof by the compression plate 11 and the rollers 17. It will be appreciated that when these rollers 17 are yieldingly compressed against the ends of the bag, they apply considerable pressure which tends to kink or 100

distort the corners of the bag which are represented by the reference numeral 24. However, by the use of the side plates 7 which retain the side walls of the bag from spreading or bulging outwardly or being distorted, the distortion of the bag at the corners 24 is eliminated and avoided.

After a piece of tape has been applied to the top of the bag, the cam 21 will pass the 10 roller 23 and the teeth and gears 20 will pass out of engagement with the rack 22, the springs 14 will then elevate the cross-head 12, while the cross-head 5 is adapted to be elevated by a coil spring 25 mounted upon one 15 of the standards 4 beneath said cross-head as shown in Figure 4.

I am aware that many changes may be made and numerous details of construction may be varied through a wide range without departing from the principles of this invention, and I, therefore, do not purpose limiting the patent granted hereon otherwise than necessitated by the prior art.

I claim as my invention:

25 1. In a bag sealing mechanism, a reciprocating member having a compression plate for engaging the top of the bag and having spaced plates for engaging the sides of the bag and a second reciprocating member having means for yieldingly engaging the ends of the bag.

2. In a bag sealing mechanism, a reciprocating crosshead having a laterally extending bar, a pair of spaced plates adjustably 35 carried by said bar, a compression plate mounted on said bar between said plates, a second reciprocating crosshead, spaced shafts carried by said crosshead, arms yieldingly mounted on and carried by said shafts, 40 and rollers carried by said arms for engaging the ends of a bag.

3. In a bag closing machine, a reciprocating member adapted for engaging the top and sides of the bag, a reciprocating member 45 having means for engaging the ends of the bag and means for simultaneously operating said reciprocating members.

4. In a bag closing machine, a pair of swingable arms, rollers carried thereby, 50 means for supporting said arms for reciprocal movement, yielding means connecting said arms, and a reciprocable member having a compression plate and a pair of spaced plates extending transversely to the axes of said rolls.

5. In a bag closing machine, a reciprocable member having yielding rollers for applying tape to the ends of the bag, and means movable in advance of said rollers for engaging the sides of the bag.

6. In a bag sealing machine, a reciprocating member embodying a compression plate for engaging the top of the bag, and a pair of spaced plates for engaging the sides of the bag, a second reciprocable member, arms piv-

oted to said second member, rollers carried by said arm for engaging the ends of the bag and yielding means connecting said arms.

7. In a bag sealing machine, the combination with a movable means for applying a piece of tape to the top of the bag, of a member movable in advance of said means for engaging the sides of said bag and embodying means for pressing down the top of the bag.

8. In a bag closing machine, the combination with means for applying a piece of tape to the top of the bag, and a reciprocable member having spaced plates for engaging the sides of the bag to prevent the same from bulging while the tape is being applied.

In testimony whereof I have hereunto subscribed my name at Chicago, Cook county, Illinois.

PAUL NAEHER.
